UNITED STATES PATENT OFFICE.

CHARLES HENRI CLAUDEL, OF LEVALLOIS-PERRET, FRANCE.

CARBURETER.

1,204,247.

Specification of Letters Patent. Patented Nov. 7, 1916.

Application filed November 10, 1913. Serial No. 800,191.

To all whom it may concern:

Be it known that I, CHARLES HENRI CLAUDEL, a citizen of the Republic of France, residing at 41 Rue des Arts, Levallois-Perret, Seine, France, have invented new and useful Improvements in Carbureters, of which the following is a specification.

This invention relates to carbureters for internal combustion engines.

10 One of the objects of the present invention is to provide an improved form of carbureter and controlling mechanism therefor which shall be particularly efficient when changing from a "no load" to a running position and during acceleration.

15 A further object of the invention is to provide means whereby a variation in the composition of the mixture suitable for a rapid acceleration may be obtained in response to rapid movements of the controlling mechanism from one position to the other.

20 A still further object of the invention is to provide improved means for effecting the operation of the valve mechanism for controlling the supply of air to the carbureter and the supply of combustible mixture issuing therefrom.

25 Another object is to provide improved means for by-passing combustible mixture around the main controlling mixture valve when the latter is in its closed position.

30 For the purpose of illustration but with no idea of limiting this invention to a particular form of device I have chosen an embodiment of the invention and have illustrated the same in the drawings, in which—

35 Figure 1 is a view in sectional elevation of a well known form of carbureter with the invention applied thereto, Fig. 2 being an outside view also in elevation of the carbureter illustrated in Fig. 1. Fig. 3 is a sectional plan view of the air valve illustrated in Figs. 1 and 2 and taken on the line 40 III—III of Fig. 2, and Fig. 4 is a view similar to Fig. 1 showing an improved by-pass arrangement for the combustible mixture when the main throttle valve is in its closed position.

45 Referring now to Figs. 1 to 3, the carbureter is shown as comprising a cylindrical body portion 1 within the interior of which the main controlling throttle, or mixture valve 2 is located. The controlling valve 50 2 is shown as composed of a cylindrical member having a passage 3 passing therethrough,

the passage 3 conforming to the shape of the passages 4 and 4' constituting the upper and lower portions of the carbureter. The valve 2 controls the supply of air to the passage 3 surrounding the jet and constituting the carbureting or vaporizing chamber and also the supply of combustible mixture from this chamber to the portion 4' of the carbureter, through the ports *a* and *b*, that is to say the lower and upper openings of the passage 3 in the valve 2 as is now well known and as will be apparent from an inspection of Fig. 1 of the drawings. A notch *a'* is provided in the valve 2 to accommodate the nozzle *g* so that the valve 2 may be opened or closed as desired. Located at the base of the carbureter is a rotary air valve 6 having a number of ports 6' coöperating with a similar number of ports 5' formed in an outer sleeve 7b or casing 5 surrounding the rotary valve. The rotary valve 6 is provided with an outwardly extending arm or projection 7, the latter of which is engaged by a bifurcated member 8 by means of which the rotary valve 6 is adapted to be rotated. The rotation of the mixture valve 2 is effected by means of a lever 10 rigidly attached to the shaft 9 supporting the valve 2. One of the outer extremities of the shaft 9 is provided with a toothed member 11 coöperating with a toothed sector 12 formed on or attached to the upwardly extending extremity of a two-armed lever pivotally mounted at 13. The opposite end 14 of this lever is connected by means of a spring or springs 15 to the upper limb of a T-shaped member 16, the downwardly depending portion of which constitutes the operating member for the rotary air valve 6, one extremity of the upper portion of the member 16 being connected to a dash-pot or retarding device here shown as comprising a piston member 17 located within a cylinder 18 having restricted ports 19 establishing communication between the interior of the cylinder and the atmosphere.

55 From the above description and from an inspection of the drawings it will be seen that when the valve 2 is suddenly moved from its closed to its open position either when starting from the "no load" position or during acceleration, the movement of the lever 10 will be immediately transmitted to the valve 2 and the valve 2 will at all times assume a position corresponding to the position of the lever 10. When the shaft 9 car-

rying the valve 2 is rotated, a corresponding movement of the lower extremity 14 of the double-armed lever will be obtained, the upper extremity of this lever being moved 5 in the direction indicated by the arrow *f* in Fig. 2 with the result that this motion will be transmitted through the spring 15 to the rotary air valve 6 and a corresponding movement of this valve 6 will eventually be effected. The movement of the valve 6 being retarded by the resistance offered to the movement of the T-shaped member 16 due to the action of the dash-pot or retarding device 17, 18, it will be seen that the flow of 10 air being temporarily retarded a lower degree of pressure will obtain within the passage 3 and within the portion 4' of the carbureter with the result that a larger amount of petrol or other liquid will be withdrawn 15 from the nozzle *g* which will compensate for the effects due to the inertia of the liquid. When the action of the retarding device has been overcome the rotary valve 6 will be moved to its open position, that is to say, to 20 a position corresponding to the position in which the lever 10 has been set, and normal conditions will again obtain within the interior of the carbureter.

The retarding device may be arranged to 25 retard the movement of the rotary valve 6 either when this valve is moved from the closed to the open position or vice versa, the opposite effect to that hereinabove described being produced in the latter case at 30 the time of closure of the valve. If desired the rotary slide valve 6 may be arranged to control the supply of hot air through certain of its ports, cold air being supplied through the remaining ports, a passage 20 35 for example being provided through which hot air is supplied to the interior of the carbureter, the port 21 controlling the supply of hot air passing through the passage 20 being open when the main controlling valve 40 45 2 is almost closed, the remaining ports for controlling the supply of cold air to the interior of the carbureter being so disposed that cold air is supplied to the carbureter only when the valve 2 is partly or entirely 50 55 open. Under certain conditions the port 21 may be arranged to remain open when the cold air ports are open, in addition to remaining open when the cold air ports are closed. It will be understood, however, that any suitable arrangement of the rotary valve 6 may be adopted and the control of air through this valve altered as desired to suit varying conditions.

In order to limit the movement of the 60 member 16 limiting stops 22, 23 may be provided co-operating in conjunction with a stop or projection 24 formed upon the downwardly projecting portion of the member 16. By this means the extent of opening 65 and closing of the hot and cold air ports in

the rotary valve 6 may be varied as desired and the maximum and minimum openings of these ports readily determined.

Referring now to Fig. 4, it will be seen that a small notch or groove 25 is provided in the upper portion of the rotary valve 2. This notch is the usual means for establishing communication between the interior of the valve 2, that is to say, the passage 3 in which the fuel nozzle is located and the upper portion 4' of the carbureter. With this arrangement the carbureted air impinges against the wall of the upper portion of the carbureter with the result that the combustible mixture is often unequally distributed 70 between the various cylinders. In the arrangement illustrated in this figure a passage 26 is provided for by-passing the mixture around the upper portion of the valve 2, the passage 26 leading to a small pipe or 75 nozzle 29 suitably attached to the interior of the carbureter. The rate of flow of the mixture through the passage 28 may be controlled by an adjustable screw 27, a number of small holes 29 being provided in the nozzle 28, so that the mixture is fed to the middle of the conduit 4' within the upper portion of the carbureter instead of issuing from the mixing chamber in such a manner as to impinge 80 against the wall of the carbureter. This by-pass may be used in combination with a passage 25 of smaller dimensions than has hitherto been customary, or under certain conditions the passage 25 may be omitted if desired. 95

It will be understood that the invention is not in any way limited to the particular construction and arrangement of the carbureter herein described and illustrated in the drawings, nor to the particular form of 100 mechanism by means of which the movement of the valve 2 is transmitted to the rotary valve 6 or to its equivalent, as the invention is in no way limited to the employment of any particular form of carbureter 105 or controlling mechanism. Modifications in these and other respects may be made without exceeding the scope of the invention. 110

What I claim is:—

1. In a carbureter, the combination of a 115 casing, a tubular mixture valve, a hydrocarbon nozzle arranged to discharge into the chamber within said valve, an air valve controlling the admission of air to the chamber within the mixture valve, means connecting the valves whereby movement of the mixture valve will be communicated to the air valve, and means for retarding movement of the air valve without impeding movement of the mixture valve, for the purpose described. 120

2. In a carbureter, the combination of a 125 casing having a plurality of air inlets in its side wall, a conduit for heated air communicating with one of said air inlets, a fuel jet 130

- extending into the casing, a main valve for controlling the output of combustible mixture, rotatable about an axis extending transversely of the casing, a valve within 5 the casing and rotatable about an axis extending longitudinally thereof to control the admission of air, and connections for effecting simultaneous actuation of said valves and permitting the air inlet valve to 10 move in one direction at a lower speed than the main valve.
3. In a carbureter, the combination of a casing having suitable air and fuel inlets and a mixture outlet, a valve controlling the 15 passage of combustible mixture from the casing, means providing a by-pass for combustible mixture about the mixture valve, and a nozzle extending into the casing from the outlet of said by-pass and provided with 20 a plurality of discharge openings.
4. In a carbureter, the combination of a casing, provided with suitable air and fuel inlets, a valve controlling the passage of combustible mixture to the outlet passage of 25 the casing, the casing having formed therein a conduit constituting a by-pass for combustible mixture about the valve, and a nozzle extending from said by-pass into the outlet passage of the casing to deliver the mixture at points relatively distant from the 30 walls of said passage.
5. In a carbureter, the combination of a casing having suitable air inlet and mixture outlet openings, a rotary tubular valve controlling the passage of combustible mixture to the mixture outlet, a fuel nozzle extending into the carbureting chamber or passage in said valve, and a mixture nozzle extending into the casing beyond said valve 35 and communicating with the carbureting chamber or passage in said valve when the latter is in its closed position.
6. The combination in a carbureter of a valve governing the supply of combustible 45 mixture to the outlet passage of the carbureter and also the amount of air supplied to the carbureting chamber, a rotary air valve operating in conjunction with the first-mentioned valve, a resilient connection between the two valves, a device operating to retard the movement of the air valve, means for by-passing the explosive mixture around the mixture valve and delivering it within 50 the interior of the outlet passage at a point distant from the walls of said passage, and means for regulating the flow of mixture through said by-pass connection.
7. The combination in a carbureter of a valve controlling the supply of combustible 55 mixture supplied to the outlet passage, a fuel jet located within the interior of said valve, a rotary air valve operating in conjunction with the first-mentioned valve, means for transmitting the movement of 60 the mixture valve to the air valve, means for retarding the movement of the air valve with respect to the mixture valve, means for by-passing the explosive mixture around the mixture valve, means for delivering the mixture by-passed around said valve at a point distant from the walls of the carbureter.
8. The combination in an internal combustion engine of a carbureter having a mixture valve and an air valve, a fuel jet located within the interior of the main valve, which constitutes a carbureting chamber, a 70 rotary valve operating in conjunction with the mixture valve and controlling the amount of air supplied to the carbureting chamber, means for varying the condition of the air passing through the air valve, means for transmitting the movement of the mixture valve to the air valve, a resilient connection between the two valves, a dash-pot device for retarding the movement of the air valve and a by-pass connection for 75 by-passing explosive mixture around the mixture valve.
9. The combination in an internal combustion engine of a carbureter having a valve controlling the supply of combustible mixture to the engine, a passage through said valve constituting the carbureting chamber, a fuel jet located within said passage, a valve controlling the supply of air to the interior of the carbureter, a resilient connection between the two valves, a device 80 for retarding the movement of the air valve with respect to the mixture valve, an adjustable by-pass connection around the mixture valve, and means for delivering the mixture by-passed around said valve to a point within the interior of the carbureter 85 distant from the walls thereof.
10. The combination in a carbureter of a valve controlling the output of combustible mixture, a passage within the interior of said valve constituting the carbureting chamber, a fuel jet located within said passage, a second valve operating in conjunction with the first-mentioned valve and controlling the supply of air to the interior of the carbureter, a resilient connection between the two valves, a device operating to retard the movement of one of the valves with respect to the other valve, a by-pass connection around the mixture valve permitting the passage of explosive mixture when said mixture valve is in its closed position, means for varying the capacity of the by-pass, and means for delivering the mixture thus by-passed to a point distant from the walls of the carbureter.
11. The combination in a carbureter of a valve controlling the output of combustible mixture and having a passage therein constituting the carbureting chamber, a fuel 120 jet located within the interior of the carbureter, a mixture valve located within the interior of the carbureting chamber, a second valve operating in conjunction with the mixture valve and controlling the supply of air to the interior of the carbureter, a resilient connection between the two valves, a device operating to retard the movement of one of the valves with respect to the other valve, a by-pass connection around the mixture valve permitting the passage of explosive mixture when said mixture valve is in its closed position, means for varying the capacity of the by-pass, and means for delivering the mixture thus by-passed to a point distant from the walls of the carbureter.
12. The combination in a carbureter of a valve controlling the output of combustible mixture and having a passage therein constituting the carbureting chamber, a fuel 125 jet located within the interior of the carbureter, a mixture valve located within the interior of the carbureting chamber, a second valve operating in conjunction with the mixture valve and controlling the supply of air to the interior of the carbureter, a resilient connection between the two valves, a device operating to retard the movement of one of the valves with respect to the other valve, a by-pass connection around the mixture valve permitting the passage of explosive mixture when said mixture valve is in its closed position, means for varying the capacity of the by-pass, and means for delivering the mixture thus by-passed to a point distant from the walls of the carbureter.
13. The combination in a carbureter of a valve controlling the output of combustible mixture and having a passage therein constituting the carbureting chamber, a fuel 130 jet located within the interior of the carbureter, a mixture valve located within the interior of the carbureting chamber, a second valve operating in conjunction with the mixture valve and controlling the supply of air to the interior of the carbureter, a resilient connection between the two valves, a device operating to retard the movement of one of the valves with respect to the other valve, a by-pass connection around the mixture valve permitting the passage of explosive mixture when said mixture valve is in its closed position, means for varying the capacity of the by-pass, and means for delivering the mixture thus by-passed to a point distant from the walls of the carbureter.

- jet located within said passage, a rotary air valve having a number of ports and passages coöperating with similar ports and passages formed within a sleeve surrounding said valve, means for delivering both cold and hot air to said ports and passages, a resilient connection between the two valves, means for retarding the movement of one of said valves with respect to the other, 5
10 a by-pass connection around the mixture valve, an adjustable member for varying the capacity of said by-pass connection, and means for delivering the mixture thus bypassed to a point in the carbureter distant 15 from the walls thereof.
12. The combination in a carbureter, of a casing having a plurality of air inlets

formed in its side wall, a tubular mixture valve, a fuel nozzle extending into the interior of the mixture valve, a sleeve valve 20 adapted to open and close the air inlets, means for turning the air valve when the mixture valve is operated, including a resilient connection, and means for retarding movement of the air valve in one direction, 25 for the purpose described.

In testimony whereof I have signed my name to this specification in the presence of two subscribing witnesses.

CHARLES HENRI CLAUDEL.
